UNITED STATES PATENT OFFICE

2,146,490

STRAW PACKAGING MACHINE

John J. Toolan, Chicago, Ill., assignor, by mesne assignments, to Maryland Paper Products Company, Baltimore, Md., a corporation of Maryland

Application July 6, 1934, Serial No. 734,056

29 Claims.

(Cl. 93—3)

My invention relates to machines for packaging drinking straws or other similar tubular articles.

It has for an object to provide a machine which will take a selected number of straws (one or more, two being the number in the embodiment of the invention illustrated) and by a continuous, as distinguished from an intermittent, action feed the straws and the envelopes or wrappers, insert the straws into the wrappers, seal the wrappers and deliver the packages from the machine.

Another object is to provide a machine in which the wrappers are formed, the straws inserted therein, the ends of the wrappers sealed, and the packages selectively discharged from the machine in predetermined groups (two groups in the embodiment illustrated).

Further, it is an object to provide a straw packaging machine in which the wrappers are formed from a continuous strip of paper and on which is printed certain selected matter by a mechanism which prints a predetermined number of inscriptions alternating with one another so that two (or more) orders for printed wrapped straws may be run out of the same machine without the necessity of changing the type set-up (when two set-ups are used every other straw wrapper will be the same), and selectively to discharge the packages from the machine so that all packages having like printed matter will be gathered together.

Further, it is an object to provide a straw packaging and printing machine in which provision is made whereby different colors may be printed on the wrappers through a simple adjustment of an ink roller carriage without the necessity of removing and replacing the ink roller from and to the machine.

Another object is to provide a machine of a rugged construction, a large capacity, provided with suitable safety devices for stopping the machine if and when something goes wrong, as for instance, if the straw hopper becomes empty or the paper strip becomes broken or the straws fail to enter the wrapper filling units, or if the straws pile up in the feeding or filling mechanism in a manner which would tend to jam the machine or cause it to deliver defective packages.

Again, it is an object to provide, in a straw wrapping machine, a wrapper carrying drum-like unit that receives the wrappers from the forming mechanism and holds them in a position to receive the straws from a rotary straw receiver and wrapper loading unit, means being pro-

vided for simultaneously sealing the ends of the stuffed wrappers.

Further, it is an object to provide a machine for the purposes described wherein the wrappers are held by suction to the wrapper carrying unit and in proper positions to receive the straws and to cooperate with the wrapper end closing-crimping rolls.

Further it is an object to provide an improved straw hopper and feeding means for feeding the straws in selected groups (pairs in the embodiment illustrated) to the straw receiver.

Further it is an object to provide improvements and refinements in the various parts of the machine to the end that the machine will be highly efficient in its operation.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, and then be particularly pointed out in the appended claims, reference being had to the accompanying drawings, in which:

Figures 1A and 1B when joined on the lines A—B constitute a plan view of the complete machine.

Figures 2A and 2B when joined on the lines A—B constitute a front elevation of my machine.

Figures 3A and 3B when joined on the lines A—B constitute a rear elevation of the machine.

Figures 4 to 8 inclusive are cross sections on the line 4—4 of Figure 2A and show the sequence of positions of the devices which deposit the wrappers into the holders of the wrapper carrying unit.

Figure 9 is a cross section on the line 9—9 of Figure 1A showing the wrapper-tube cutting mechanism.

Figure 10 is a detail perspective view of the scissors, the principal parts thereof being separated.

Figure 11 is a cross section on the line 11—11 of Figure 3B, showing the straw feeding mechanism.

Figure 12 is an end elevation of the structure shown in Figures 1A and 2A and 3B, looking from left to right in Figure 3B; the parts in section 50 are taken on the line A—B in Figure 3B.

Figure 13 is a detail cross section on the line 13—13 of Figure 3B.

Figure 14 is a detail perspective view of the funnel end of a straw receiving slide.

- Figure 15 is a detail perspective view of the other end of a straw receiving slide.
- Figure 16 is a detail end elevation of the slide and its retainer, part being broken away.
- Figure 17 is a detail perspective view of the pushing end of the straw inserting push-bar.
- Figure 18 is a detail perspective view of one of the cross-heads.
- Figure 19 is an edge elevation of one of the straw selector wheels.
- Figure 20 is a side elevation thereof.
- Figure 21 is a detail vertical longitudinal section showing the vacuum or suction means to hold the wrappers to the wrapper-holding bars of the wrapper carrier.
- Figure 22 is a detail perspective view of one of the wrapper-holding bars.
- Figure 23 is a detail elevation of the detachable block of one of the safety devices.
- Figure 24 is an enlarged detail front elevation of the wrapper forming mechanism.
- Figure 25 is an enlarged detail elevation and part section showing the means to lubricate the inner longitudinal seam-sealing roller.
- Figure 26 is a further enlarged detail plan view of a portion of the apparatus shown in Figure 25.
- Figure 27 is a detail section of a part of the printing cylinder.
- Figure 28 is a detail perspective view of one of the plate or type carriers for the printing cylinder.
- Figure 29 is a detail section on the line 29—29 of Figure 28.
- Figure 30 is a detail elevation of a portion of the platen wheel.
- Figure 31 is a detail vertical section of the structure shown in Figure 30.
- Figure 32 is a detail cross section on the line 32—32 of Figure 39.
- Figure 33 is a detail perspective view of the longitudinal seam-lapping die.
- Figure 34 is an enlarged detail section on the line 34—34 of Figure 24.
- Figure 35 is a detail cross section on the line 35—35 of Figure 26.
- Figure 36 is a detail perspective view of the safety device used when a break in the continuity of the paper strip occurs or the end of the roll of paper has been reached.
- Figure 37 is a detail elevation of the two-part printing wheel with the parts separated.
- Figure 38 is a detail perspective view of one of the adjustable pivot plates.
- Figure 39 is an enlarged detail section on the line 39—39 of Figure 1B.
- Figure 40 is a circuit diagram of the safety devices showing how they cooperate with the driving motor.
- Figure 41 is a detail view later referred to.
- In the drawings in which like numerals of reference indicate like parts in all of the figures it will be observed that the machine comprises several major units, namely: the printing mechanism, the continuous wrapper forming mechanism, the wrapper severing mechanism, the wrapper receiving mechanism, the straw feeding and wrapper stuffing mechanism, and the package discharging mechanism.
- The machine comprises a base 1 which is supported on suitable standards 2. Held in a bearing 4 in an end standard 3, and in a corresponding bearing 104x in a standard 104, is the main shaft 5 of the package and straw assembling units, shown particularly in Figures 1A, 2A and 3B of the drawings. Secured to the shaft 5 are disks 7, 8, 9, 10, 11 and 12, and mounted on the shaft 5 is a barrel-cam 18 having a hub portion on which is rotatably mounted a ring-like disk 6. The cam is held from rotating by a locked screw 35. Pairs of guide bars 13 are secured to 5 and between the disks 6 and 7, constituting there-with a rotatable drum-like skeleton. In the embodiment illustrated there are six pairs of guide bars disposed sixty degrees apart. The bars 13 have longitudinal slots 14 constituting guideways 10 for the cross-heads 15 which are mounted to be reciprocated along the guide bars by means of rollers 28 which engage in a cam groove 19 of the cam 18. Secured (preferably adjustably) on each cross-head 15 is a pivot plate 21 which 15 has a stud 17 to which a push-bar 16 is pivoted. Mounted in radial slots in the disks 7, 8, 9 and 10 is a set of straw receiving slides 22 each of which has a longitudinal straw receiving groove 23 of a width to take the number of straws that 20 the machine is designed to place in one package (two straws to the package in the illustrated embodiment of my invention). Each slide 22 has grooves 24 (forming with the groove 23 a T-slot). A push-bar 16 operates in each groove 23. The 25 bar 16 has suitably located wings 30 in the grooves 24 to guide and steady the bar as it is moved longitudinally in the groove 23.
- In order to hold the slides 22 in place on the disks 7, 8, 9 and 10 retainers 29 are secured to 30 the disks 8, 9 and 10. These retainers (see Figures 2A, 15 and 16) have fingers 28 which enter longitudinal grooves 25 in the slides 22 as shown.
- At the front end of each slide is secured a plate 26 which carries a funnel member 27 that is designed to be inserted in one open end of a wrapper W and through which funnel the straws S are passed into the wrappers. Each slide 22 is also provided with a pair of spaced cross-grooves 31 (see Figures 2A and 14), the purpose of which 40 will later appear.
- The front end of each push-bar 16 is provided with a number of prongs 32 (the number depends on the number of straws to be placed in a package). These prongs 32 are adapted to enter an 45 open end of the straw and hold the same to move simultaneously forward through the funnel 27 into the wrapper W with which it is cooperating.
- The slide 22 is given a slight longitudinal stroke, enough to bring the funnel 27 into and remove it 50 from a wrapper W, by means of a cam groove 33 in the cam 18 with which groove a roller 34 on each slide engages.
- The parts 5 to 34 inclusive constitute the rotary straw receiving and delivering sub-unit of the 55 machine.
- The wrapper receiving and holding mechanism includes the disks 11 and 12 on the shaft 5. To the peripheries of these disks are secured a set (six in the embodiment illustrated) of wrapper 60 receiving and holding bars 36 (one being shown in perspective in Figure 22). Each bar 36 includes a groove 37 comprising a seat for the wrapper. The bar is cut away to leave transverse spaces 38 and it is also provided with ears 65 39 by which it is secured to the disks 11 and 12.
- Two methods are disclosed in the illustrated embodiment of the invention for preventing the wrappers from falling out of the grooves 37, either or both of which may be used at the same time in 70 the machine as may best suit the designer. One method consists in the provision of suitably located guides 40—40'—203 (see Figures 4 and 13), the guide 40' being centrally located and the guide 40 being located near the end. An end- 75

stop plate 339 serves to hold the wrappers against endwise movement while the funnels 27 are being inserted, while a yieldable tension finger 204 (see Figure 13) places sufficient tension on the package WS while the funnel 27 is being withdrawn, to hold the package against following the funnel. The finger 204 is pivoted at 206 on a support 208 and is held in pressure contact with the package WS by a spring 207, there being a stop 205 provided to restrain the inward movement of the finger 204.

The other method consists in a vacuum or suction means (see particularly Figures 1A, 9 and 21). In this method the bars 36 are provided with longitudinal ducts 65 having branches 66 to each section of the elements which have the grooves 37. Each bar also has a port 68 communicating with a port 67 in the disk 12. An air distributing disk 69 is held on the shaft 5 against rotation by a bar or bracket 74 and is held in air-tight contact with a face of the disk 12 by a spring 70 and collar 71 on the shaft 5. The disk 69 has a distributing groove 73 which extends from a place just beyond the wrapper receiving position to a place just in advance of the package removing position (see Figure 9), so that immediately after the wrapper has been deposited in the groove 37 of a bar 36 it will be held against movement in any direction until it has been stuffed and brought to a place adjacent the end crimping rolls and the place where the package is removed from the bar 37 for delivery from the machine. Connection to any suitable suction source (not shown) is made by means of a duct 72. When the suction method is employed the elements 40, 40', 203, 204 and 339 may be omitted or used simply as safety means in case the suction fails.

The mechanism which receives the cut sections of wrapper and delivers them into grooves 37 of the proper bars 36 is best shown in Figures 1A and 2A and 4 to 8 inclusive, by reference to which it will be seen that 75 indicates a fixedly mounted bracket which carries suitably spaced wrapper guide and stop blocks 76 that line up with the grooved sections of the bars 36. Envelope receiving fingers 77 are carried by a movable bar 78 and line up with the spaces 38 (see Figures 2A and 4). The bar 78 is carried by an arm 79 and lever 80, the latter having a roller 81 to engage a cam 82 on the cam-shaft 90. The arm or bar 79 and the lever 80 are respectively pivoted to arms 83 and 84. The arms 83 and 84 are rotatably mounted on the fixed shaft or rod 103 and are connected together to move as one by a yoke 102. The arms 83 and 84 are rocked through an arm 85 having a roller 340 engaged by a cam 341 on the cam-shaft 90.

Upper wrapper guiding and placing fingers 86 are carried by a bar 87 which is rigidly secured to the lever arm 88 and arm 89. The arms 88 and 89 are respectively pivoted to arms 93 and 94 which are rotatably mounted on the rod 100 and are connected together to move as one by a yoke 101. The lever arm 88 has a roller 91 that engages the cam 92 on the shaft 90. The roller 91 is held in contact with its cam by a spring 98, while the roller 81 is held to its cam by a spring 342. Springs 99 pull down on the arms 83 and 93. The arms 93 and 94 are moved in unison by the cam 97 which engages the roller 96 on the lever arm 95 that is rigid with the arms 93 and 94.

Standards 103 and 104 support the rod 100, the shafts 133 and 90, the standards having bearings 105 and 106 for the cam shaft 90 and bearings 134

and 135 for the shaft 133. The standard 104 has a bearing 104x for the shaft 5.

A gear 107 on the shaft 90 meshes with a gear 137 on the shaft 133. The gear 137 in turn meshes with the gear 218 on the shaft 219 hereinafter again referred to. The standard 103 and a second standard 136 have bearings 134 for the shaft 133. Mounted on the base 1 and located at the rear of the machine between the standards 103 and 104 is a casting 108 having a lower step 10 bearing 109 and an upper bearing 110 for the shaft 114 which carries a ball-thrust bearing 115 to support the weight of the shaft 114 and the parts carried thereby. The casting 108 also supports a pair of parallel rods 111 on which the scissors carriage 112 slides back and forth, the carriage having bearings 113 to fit on the rods 111. The purpose in having the carriage slide along the rods is to enable the cutting mechanism to follow the wrapper at the same speed while the wrapper is being severed and to push the severed section into properly aligned position with the wrapper receiving drum.

The shaft 114 carries a worm gear 116 that meshes with a similar gear 140 on the shaft 133. It also carries a cam plate 117, having cam members 118 to cooperate with a roller 119 on the carriage 112 for pushing the carriage in one direction; a spring 120 is provided to move the carriage in the opposite direction.

The cutter employed is a scissors-type cutter and comprises a lower member 121 and an upper member 127, gear connected at 130—131 and pivotally mounted at 123 and 129 to the bracket 343 that extends from the rear of the carriage 112. The scissors members 123 and 127 carry removable and adjustable blades 122 and 128 respectively. The scissors is operated by a cam 138 on the shaft 133, the cam having a recess-groove 139 to receive a roller 126 on the extension arm 124 that is secured to the scissors arm 121. A spring 125 closes the scissors when the roller 126 drops into the groove 139. A stop arm 132 carried by the bracket 343 prevents the wrapper from lifting when the scissors opens.

To take up end thrust on the shaft 133, due to the sliding of roller 126 along the groove 139, a ball thrust bearing 141 is provided. In order that the wrapper after it has been formed and longitudinally sealed (as will later appear) may pass between the blades of the scissors freely while the scissors are open, I provide adjacent the scissors a guide 178 having a hole 179 for the passage of the wrapper (see Figure 12).

A gear 142 on the shaft 5 meshes with a gear 143 on the straw selector shaft 144, which gear 143 in turn meshes with an idler pinion 145 that is secured to a larger gear 146, the pinion 145 and the gear 146 rotating as one on a stub shaft 147 (see Figure 41). The gear 146 meshes with a gear 148 on the shaft 143.

The article delivering mechanism which assorts the packages according to the printed matter thereon into a plurality (two in the embodiment illustrated) of groups comprises a delivering shaft 41 having a pair of disks 42 with arms 43 to receive the packages from the bars 36 and deliver them to the off-take chutes of the receivers 44 and 46, as the case may be. The lower receiver 44 is fixedly held at 45 and is designed to receive all packages not selected by the selector fingers 336 which are carried by a rocker shaft 48. The lower receiver 44 also has fingers 337, as shown in Figures 2A and 4.

The upper receiver 46 is fixedly held at 47

and it, too, has fingers 338 to cooperate with the rocking selector fingers 336. The selector fingers 336 are rocked alternately to positions to receive and pass the packages WS of wrapped straws by 5 means of a lever 49 having a roller 50 that engages with the cam 51 on the shaft 41.

The shaft 41 also carries a pair of knurled rolls 52 which cooperates with a second pair of knurled rolls 62 to seal the ends of the wrappers before 10 the packages are discharged from the machine. The shaft 41 is driven by a pinion 53 that meshes with the gear 142 and it is mounted in standards 54 that have flat tops 55 to support the bracket plates 56. The plates 56 carry bearing arms 57 15 with bearings 59 for shaft 58 on which bell-cranks 60 and 61 are pivoted; the arms 61 of the bell-cranks carry the knurled crimping rolls 62 which are held in pressure contact with the rolls 52 through the medium of the pressure adjusting 20 screws 56x.

A rod 63 is fixed to the standards 54 and carries a pair of guide fingers 64 that are passed through the spaces 38 as the bars 36 are moved by. Thus the fingers 64 pick the packages from 25 the bars 36 so that they may be carried over to the receivers by the arms 43.

The straw delivery mechanism

The mechanism for delivering or feeding the 30 straws from the hopper 158 to the slides 22 is best shown in Figures 1A and 11, by reference to which it will be seen that a pair of straw selector wheels 149 (see Figures 11, 19 and 20) have adjustable spring advanced fingers 150 whose lugs 35 151 are engaged by adjustable finger plates 154 that are secured to the wheels 149 by screws 155. The selector fingers 150 slide in radial slots 152 which contain the springs 153.

In order to agitate and break apart the straws 40 within the hopper 158 and prevent them from jamming, I provide a rocking shaft 160 that carries a plate 159 which constitutes the back of the hopper. The shaft 160 is rocked by an arm 161 having a roller 162 that engages a cam 163 on the straw feeding shaft 164.

The shaft 164 carries sets of brushes 165 which operate to feed the straws S forwardly along the chute-way 172—173 (see Figure 11). The shaft 164 carries a loose pulley 166 having 50 a pawl 167 to engage a ratchet 168 fixed to shaft 164, the shaft having a hand wheel 169 by which it may be turned manually, if and when desired.

The hopper 158 is supported on standards 170 and it also carries brackets 171 having bearings 55 for the shaft 164.

The straws are held down on the chute portion 172 by the plates 173 (see Figures 1A and 11) which plates are connected by a cross bar 174, the plates being carried by the hopper 158. 60 The plates 173 have straw check members 175 at their outer ends which, together with the lips 172x on the chute 172, form a throat through which the straws are delivered in selected number to the grooves 23 of the slides 22.

65 A pulley 176 on the shaft 133 drives the loose pulley 166 by means of a belt 177.

The straws are held from falling out of the 70 grooves 23 by guide 156 carried on suitable supports 157 (see Figures 3A and 11).

In order to stop the machine as the hopper 75 becomes empty or the stream of straws along the chute 172 is interrupted, I provide a safety device consisting of a support 180 carrying a block of insulation 181 in which is held a live contact 182. The contact 182 is adapted to be engaged

by a grounded contact 186 on the arm 185 of a lever that is pivoted at 184 and has a foot 183 whose heel is adapted to engage the straws S to keep the contacts separated while the flow of straws is normal. The live contact 182 leads to a relay which, when the circuit is closed, opens the motor circuit, as will later more fully appear. 5

188 designates a pair of fixed straw retaining fingers carried on a rod 187. A safety rocker arm 189 is provided with a straw engaging foot 190 having a beveled edge 191 to ride over straws and over the bars 22 on the discs 8 and 9. 192 designates a bell crank latch which is pivoted at 193 and is adapted to be engaged by a latch releasing arm 194 (see Figure 11). A cam 195 serves to move the arm 189 to a position with respect to the straw drum so as to move the foot 190 out of contact with the straws in order to preserve the straws from pressure tending to mash them. If no straws are present the arm 194 will act 20 before the cam 195 does. 196 is a safety rocker arm that is pivoted on the rod 187 and carries an electrical contact 197 on its insulated portion 198, there being a stop 199 provided to limit the rocking movement in one direction. 200 designates a 25 grounded contact (see Figures 11 and 40) which cooperates with the contact 197 to close the circuit of the relay 365 when member 196 passes an empty straw slide.

201 indicates an insulated block on the rocker 30 arm 189, the insulated block carrying an electrical contact 202 which cooperates with a pivoted circuit closing member 344, this member having a notch 345 to cooperate with the latch 192, a spring 346 being provided which tends to draw the 35 member 344 toward the latch 192. The weight of arm 189 and its parts, augmented by a spring 189x (see Figure 11), serves to hold the arm with its foot 190 normally in light contact with the drum. 40

The wrapper forming mechanism

Mounted upon standards 209 and 210 is the 45 bed 239 of the wrapper or envelope-tube forming mechanism. In suitable bearings is mounted the first motion or motor driven shaft 211 which has a gear 212 that meshes with one of the gears 216 of a double idler gear 215—216 that is mounted on a stub shaft 217. The shaft 211 is driven by a motor 364 through a belt 362. The shaft 133 has a gear 214 to mesh with the gear 215—216, there being a bearing 213 provided for the end of the shaft 133.

A gear 218 on the shaft 219 meshes with a gear 50 137 and is driven thereby. The shaft 219 constitutes what may be termed the printing mechanism driving shaft, as will later more clearly appear.

The shaft 211 has a worm 220 and a spiral gear 60 221, the latter meshing with a worm 222 on the hand-wheel 224 to operate the machine in making tests, adjustments, etc. The shaft 223 is suitably mounted in standards 225 on the base 1.

The worm 220 meshes with a spiral gear on the 65 shaft 226 which has a gear 229 that drives the gear 230 located on the stud shaft 231 which is fixed to the block 232. The shaft 226 is journaled in suitable bearings 228—228x as shown. A swinging arm 233 is pivoted to the shaft 231 and carries a crimper shaft 234, a crimper wheel 235 and a driving gear 236. A swinging arm 237 is pivoted between ears on the arm 233 and serves, in cooperation with the set-screw 238 to adjust the tension or pressure of the crimping wheel 70 75 235.

233 against the paper strip and the wheel 243 (see Figure 24).

A web 240 extending from block 232 carries a mandrel 241 around which the wrapper is formed, the mandrel being slotted as at 242 to receive the inner crimping wheel 243. A spreader 244 is mounted in and extends from the far end of the mandrel. A grease reservoir 245 extends from the near end of the mandrel and has a screw plunger 348 to force grease through a duct 349 to the bore 350 in the shaft in the wheel 243 in order to lubricate its bearings. 351 designates paper guides on the mandrel 241.

Paper guide members 246 are adjustably and resiliently mounted on the bracket 251 by studs 248. The members have overturned edge plates 247 (see Figure 34), to guide the side edges of the continuous strip of paper P. The studs 248 are carried by a plate 249, project through holes in the members 246 and have nuts 248a for holding the bars or members 246 against the tension of the springs 352.

The bracket 251 is carried by the sub-base 250.

A bevel gear 254 on the shaft 219 drives another bevel gear 254a on a shaft 255 which is journaled in bearings 257 and carries another bevel gear 256 (see Figure 1B) that meshes with the bevel gear 259 on the shaft 258 that carries the spur gear 260 which meshes with the spur gear 261 on the shaft 262 that carries the grooved paper-feed-rod 263.

Secured in a bracket 253 is a rod 264. The rod 264 carries adjustably a rod 265 which has an adjustable bracket 266 for the stud shaft that carries the guide pulley 267 which guides the paper strip. A tension device including a rockable arm 268 carrying a tension roller 354 and pivoted at 355 is provided for use when desired to take up slack in the paper strip.

A presser roller 270 is carried by an arm 269 that is pivoted at 258 and is held pressed against the grooved roller 263 by a spring 271. It may be held down away from the roller 263 by a pivoted bar 272 that can be swung to the position shown in dotted lines in Figure 24.

The paper is guided by being passed over the pin 273 which is carried by the lever 269 and adjacent the pin is a safety device finger 274 that lies on the paper strip and is carried by a shaft 275 mounted in a bearing 276 on the base 279. (See Figure 36.) An arm 277 on the shaft 275 makes contact with a live contact 278 on an insulated support that is mounted on the base 279 whenever the paper strip breaks or the end of the roll has been reached.

On a plate 280 is a paper guide block 281 which carries the longitudinal edge-folding-over dies 282 (see Figure 33).

The printing mechanism

This mechanism is designed to print the desired matter on the wrapper. By means of my invention two or more (two being illustrated in the present embodiment of the invention) different sets of printing matter may be placed on the continuous strip P alternately for the purpose of filling different orders if desired. The strip printing mechanism includes standards 283 on which is mounted a bed plate 284 that carries beveled strips 285 which are spaced apart to provide a guide-way for the base 286. The base 286 is slidably and adjustably held crosswise of the machine and is held in place by the strips 285. The base 286 carries the end plates 287 of the inking mechanism which includes inking rolls 288 and

292 with spaces 289 between the inking surfaces of the same. The inking rolls are mounted respectively on the shafts 290 and 291. The inking mechanism comprises the parts which are mounted between the end plates 287 on the standards 286 and are of the same construction and combination as those found in a well-known multi-graph machine now on the market, except that the inking rolls 288 and 292 instead of being continuous have the cut away places 289 (see Figure 13).

The different portions of the rolls 288 and 292 may be inked with different colored inks, so that when it is desired to use a different color it is only necessary to adjust the carriage standard 286 crosswise of the machine to line up the desired colored section of the inking roll with the printing roll.

The rolls 288 and 292 are geared together by a gear train 293 which is driven by the spur gear 356 that meshes with a gear 315 on the printing wheel shaft 314. The gear 315 in turn meshes with the gear 296 on the shaft 295 of the platen roll. The shafts 314 and 295 are mounted in bearings on standards 294.

The platen roll 297 is provided with a tacky surface so that the paper strip will adhere slightly thereto. The platen roll shaft 295 has eccentric portions 295a, one of which is mounted in a bearing of the back standard 294, while the other is mounted in an eccentric bushing 306 in a bearing in the front standard 294. The bushing 306 has an arm 303a (see Figures 26 and 32) secured adjustably by a set screw 303b.

The platen is raised and lowered by a lever 303 that is secured to the front end of the shaft 295. The arm 303a is used to justify the platen roll to the type by tilting the shaft 295 at one end. The lever 303 serves to raise and lower the shaft 295 parallel to itself in order to clear or to contact the type wheel as the case may be.

By reference to Figures 30 and 31 it will be seen that the platen roll has recesses in which are located rods 308 and 309, the former being rotatable and the latter being fixed. A band of live rubber or composition 307 has one of its ends fastened to the rod 309, while the other end is secured to the rod 308. The rod 308 has a ratchet disk 310 with which a pawl 311 cooperates. The exposed end of the rod 308 has a kerf for a screw-driver by which it may be turned to stretch the band 307 taut around the wheel.

Between the upper inking roll 292 and the platen 297 is a splash guard 312 to prevent the ink from being thrown onto the printed paper strip (see Figure 26). The paper passes from the roll on the stand 331 over a guide roll 313 before passing under the platen 297. 304 and 305 indicate stop pins.

The platen 297 has a sleeve 300 with notches 301 in its end to fit lugs of a coupling washer 302 which has other lugs fitting notches 299 in the hub 298 of the gear 296. This structure permits the justifying and the raising or lowering of the platen without causing binding of the gear 296 or throwing it out of line with gear 315.

The printing wheel is designated by 316. It is composed of two half sections each having a split-clamp hub 318 and side flanges 317, the latter having notches 319 to receive the lugs 329 of the type carrier segments 326. The wheel sections 316 are bored and are provided with bearing seats for the pivots 321 of the locking plates or latches 320 (there being one on each side of the wheel). These plates 320 are connected by tie rods 324 and

pivots 321, the tie rods 324 passing through holes 323 in the webs of the wheel sections 316 (see Figure 27). The latch plates 320 have fingers 322 which are undercut to fit over the lugs 329. Handles 325 are provided by which the latch plates 5 may be moved on their pivots 321 to lock or release the pins 329 and consequently hold the type or plate carrying members to the periphery of the wheel or release the same, as the case may be.

10 A spring 357 serves yieldably to hold the pivots 321 to their seats. The type carrier segments are made of laminated parts with grooves 328 forming T-slots in the peripheries thereof (see Figures 28 and 29), in which grooves type are set or a 15 plate 330 may be held. The laminae are secured together by cross bolts and nuts 327. The roll of paper stand 331 supports a friction drag comprising a flexible strap 332 to lie over the periphery of the paper roll, the strap being suitably 20 weighted at its free end.

The shaft 219 drives the printing wheel through bevel gears 333 and a shaft 334 which has a gear 335 to mesh with the gear 315 (see Figure 3A). The machine is driven from a suitable electric 25 motor (not shown) by a driving belt 362 taking over a pulley 361 on the shaft 211.

A counter 358 may be provided and operated by a connecting rod 360 from a crank 359 on the shaft 90.

30 Paper drinking straws are usually covered with paraffin. The paraffin sometimes causes the straws to stick together. When this occurs in the hopper 158 the swinging member 159 serves to break the adhesion so that when the straws pass 35 under the member 159 they will be free of one another.

The shaft 363 has a pinion 356 which meshes with the gear 296 to drive the gear train 293.

In Figure 40 is shown a circuit arrangement 40 for the motor control. In this figure 364 represents the motor, 370 its electric circuit which includes the armature 366 and the fixed contact 367 of a relay which is designed to be locked open by means of a latch lever 368. The latch 45 may be manually released by pushing on the button 367 when the motor circuit is to be closed.

The relay magnet 365 is energized to open the motor circuit when one or another of the safety devices hereinbefore referred to operates, as will 50 clearly appear upon inspection of Figure 40.

Operation

From the foregoing it is thought that the operation of the invention will be clear. However, 55 a brief resume of the operation will now be given.

Assume that the hopper is filled with straws and a reel of paper is being carried by the support 331.

Assume, further, that the printing wheel 316 60 is provided with two different type set-ups one on each carrier 326 so that the machine at the same time may print two distinct wrappers as hereinbefore pointed out. Assume, further, that the paper P has been passed around the guide 65 313, under the platen 297, over the grooved pulley 261, under the grooved paper feeding roll 263 and threaded between the paper upturning members 246, under the mandrel 341, and through the folding-over dies 282. As the folded 70 over paper passes between the serrated crimping wheels 235 and 243 it will be secured together longitudinally in the form of a tubular wrapper W (see Figures 1B and 2B). This wrapper as it passes from the longitudinal crimping wheels 75 243—235 is spread laterally by the fingers 244

until the wrapper tube assumes a somewhat elliptical cross section.

As the paper passes around the platen roll 297 it is printed in alternate lengths by the type or plates on the printing wheel 316 with the desired advertising or trade-mark matter. 5

In passing from the printing and forming mechanism which is shown particularly in Figures 1B, 2B and 3A (see also Figures 24, 25, 26 and 29), the wrapper passes through the wrapper 10 or envelope guide 178 (see Figure 12) and between the opened blades 121—127 of the shears (see Figure 9) and beneath the stop arm 132.

The wrapper W passes along above the wrapper receiving fingers 77 and below the wrapper 15 guide and stop blocks 76. As the wrapper travels along a section of the wrapper will be cut off at the proper time by the shears, shown in Figures 9 and 10, and the blade 127—128 of the shears will push the cut section of the wrapper along 20 so that it lines up properly with the wrapper receiving and holding drumlike unit composed of the disks 11 and 12 and the bars 36 carried thereby. As the wrapper approaches its position for being deposited into the grooves 37 of a receiving bar 36 it will be engaged by the members 76, 77 and 86 and placed by the members 77 and 86 into the grooves of a bar 36 as that bar comes into position beneath the wrapper; the movements which take place in receiving the wrapper 30 and laying it into the grooves 37 of a bar 36 are illustrated in their different times of movement throughout a cycle, in Figures 4 to 8 inclusive of the drawings. By reference to these figures it will be noted that with the machine positioned 35 as shown in Figure 4 a wrapper has not yet come into position between the members 76 and 77. By the time the shaft 5 has turned from the position shown in Figure 4 to that shown in Figure 5, however, a wrapper will have come into position 40 to be received by the fingers 77. At the same time the guide fingers 86 will be moving downwardly toward the wrapper. Now as the parts move from the position shown in Figure 5 to that shown in Figure 6 the fingers 77 have moved 45 downwardly somewhat further toward the bar 36 beneath the same. Continuing the movement from Figure 6 to Figure 7 it will be seen that the fingers 77 have located the wrapper W in the grooves of the bar 36 beneath and are beginning to leave the wrapper which is held down at this time by the fingers 86. Further movement from the position shown in Figure 7 to that shown in Figure 8 shows that the fingers 77 are lowered 50 sufficiently to clear the wrapper which allows the wrapper to be moved clear of the fingers 77 and 86. As the parts move from the position shown in Figure 8 back to the position shown in Figure 5 the cycle will have been completed.

By the time the wrapper arrives at the upper 60 right hand position shown in Figure 4 the straws will have become partly inserted into the wrapper and by the time the lower left hand position shown in Figure 8 is reached they will have become fully inserted into the wrapper and the 65 push bar 16 will have been retracted from the wrapper.

Let us now pass for a moment to the straw delivery mechanism (refer particularly to Figures 1A, 3B and 11). As will be seen by reference to 70 Figure 11, as the straw receiving drum-like unit, composed of the disks 8, 9 and 10 and parts carried thereby, moves in the direction of the arrow on the disk 9 in Figure 11 the selector fingers 150 at the right in Figure 11 will take the first 75

two straws and deliver them into the groove 23 of the straw receiving slide 22 just beneath the same. The straws are fed down the chute 172 by the brushes 165, aided by gravity. As soon as the straws have been placed in the receiver 22, the push bar 16 cooperating with that receiver will be advancing to enter its projections 32 into the adjacent ends of a pair of straws. In the meantime the cam 33 will have advanced the straw carrier 22 to insert its funnel 21 into the wrapper which has lined up with it so that as the movement of the machine continues the cam-way 19 will advance the push bar 16 to deliver the pair of straws through the funnel 21 and insert the straws completely in the wrapper by the time the unit under discussion reaches the lower left hand position in Figure 11 and from that time on the push bar 16 recedes so that by the time the unit 22 under discussion reaches the position at the lower right in Figure 11 the bar 16 will have been fully withdrawn. As the package of wrapped straws arrives at a position shown at the left in Figure 8 the package of straws on further movement is carried between the end crimping wheels 52-62 and the ends of the package are crimped shut or sealed. By this time an arm 43 on each delivery disk 42 will have come up under the package of straws to carry it upwardly and outwardly away from the crimping disk through the positions shown in Figures 5, 6, 7 and 8 and deliver them either into the receiver 46 or 44 as the case may be, accordingly as the fingers 336 are inwardly directed (see Figure 5), or outwardly directed (see Figure 4), it being understood that all alternate packages are shunted by the fingers 336 onto the receiver 46, while the remaining packages pass directly into the receiver 44. This completes the cycle of operation.

The operation of printing the wrappers, severing the continuous tube into wrapper lengths, delivering those lengths onto the wrapper receiving drum-like unit, the feeding of the straws into the straw receiving unit, the insertion of the straws into the wrapper sections, the sealing of the ends of the wrapper sections simultaneously and the selective delivery of the packages into the receivers takes place as a continuous operation so long as the machine is acting normally. However, should the supply of straws in the hopper run out, for instance, the foot 183 will drop, close the circuit between 185 and 182 and thereby energize the magnet 365 which instantly opens the motor circuit and stops the machine, the latch 368 keeping the circuit open until the attendant is ready to close it again by pushing the button 367.

Should only one straw be fed to a receiver 22 or should the receiver pass without receiving any straw, the safety device 189 will come into operation to close the circuit between elements 202 and 344 (see Figures 11 and 40) and thereby energize the relay magnet 365 to stop the machine. Also, if more than two straws enter the receiver 22 or the straws do not lie properly in the receiver the safety device 196 will come into operation to close the relay magnet circuit between elements 197 and 200 to stop the motor. If the end of the paper reel is reached the safety device 274 will operate to close the circuit between 277 and 278 and stop the motor.

While I have primarily designed my machine for packaging drinking straws, it is obvious that it may be used for packaging other similar tubular articles. Therefore, in the claims where I refer to "straws" I desire that term to be con-

structed broad enough to include other similar tubular articles and do not wish it to be limited solely to drinking straws.

From the foregoing description, taken in connection with the accompanying drawings, it is thought that the construction, combination and operation of the invention will be clear to those skilled in the art, and I wish it understood that changes in the details of construction and arrangement may be made without departing from the spirit of the invention and scope of the appended claims.

What I claim is:

1. In a straw packaging machine, a rotatable shaft, two members carried by said shaft and having superficial grooves which travel in alignment with each other, the grooves in one of said members being constructed and adapted to receive wrappers, reciprocatable straw receiving members in the grooves of the other member, push-bars operating in and through said straw receiving members to force the straws from the straw receiving members, means for delivering straws to said straw receiving members, means for delivering wrappers to the first of said two members, means for sealing the ends of the filled wrappers, and means for removing the filled wrappers from the first of said two members.

2. In a straw packaging machine, a rotatable shaft, two members carried by said shaft and having superficial grooves which travel in alignment with each other, the grooves in one of said members being constructed and adapted to receive wrappers, straw receiving members in the grooves of the other member, push-bars operating in and through said straw receiving members to force the straws from the straw receiving members into the wrappers, means for delivering straws to said straw receiving members, means for delivering wrappers to the first of said two members, means for sealing the ends of the filled wrappers, and means for removing the filled wrappers from the first of said two members, said straw receiving members comprising slides having funnels to enter the wrappers, and means to advance and retract said slides for inserting the funnels into the adjacent ends of the wrappers before the straws are pushed into the same and to withdraw the funnels thereafter.

3. In a straw packaging machine, a rotatable shaft, two members carried by said shaft and having superficial grooves which travel in alignment with each other, the grooves in one of said members being constructed and adapted to receive wrappers, straw receiving members in the grooves of the other member, push-bars operating in and through said straw receiving members to force the straws from the straw receiving members into the wrappers, means for delivering straws to said straw receiving members, means for delivering wrappers to the first of said two members, means for sealing the ends of the filled wrappers, means for removing the filled wrappers from the first of said two members, said straw receiving members comprising slides having funnels to enter the wrappers, and means to advance and retract said slides for inserting the funnels into the adjacent ends of the wrappers before the straws are pushed into the same and to withdraw the funnels thereafter, said slide advancing and retracting means including a cam having a cam-way and said slides having projections entering said cam-way, said cam having another

cam-way and said push-bars having projections to enter said another cam-way.

4. In a straw packaging machine, a rotatable shaft, two members carried by said shaft and having superficial grooves which travel in alignment with each other, the grooves in one of said members being constructed and adapted to receive wrappers, straw receiving members in the grooves of the other member, push-bars operating in and through said straw receiving members to force the straws from the straw receiving members into the wrappers, means for delivering straws to said straw receiving members, means for delivering wrappers to the first of said two members, means for sealing the ends of the filled wrappers, means for removing the filled wrappers from the first of said two members, said straw receiving members comprising slides having funnels to enter the wrappers, means to advance and retract said slides for inserting the funnels into the adjacent ends of the wrappers before the straws are pushed into the same and to withdraw the funnels thereafter, and means to hold the wrappers against endwise movement while said funnels are being inserted and withdrawn.
5. In a straw packaging machine, a rotatable shaft, two members carried by said shaft and having superficial grooves which travel in alignment with each other, the grooves in one of said members being constructed and adapted to receive wrappers, straw receiving members in the grooves of the other member, push-bars operating in and through said straw receiving members to force the straws from the straw receiving members into the wrappers, means for delivering straws to said straw receiving members, means for delivering wrappers to the first of said two members, means for sealing the ends of the filled wrappers, means for removing the filled wrappers from the first of said two members, said straw receiving members comprising slides having funnels to enter the wrappers, and means to advance and retract said slides for inserting the funnels into the adjacent ends of the wrappers before the straws are pushed into the same and to withdraw the funnels thereafter, said slide advancing and retracting means including a cam having a cam-way and said slides having projections entering said cam-way, said cam having another cam-way and said push-bars having projections to enter said another cam-way, and means to hold the wrappers against endwise movement while said funnels are being inserted and withdrawn.
6. In a straw packaging machine, a rotatable shaft, two groups of disks secured to said shaft, wrapper receiving bars secured to one group of disks, straw receiving slides mounted on some of the disks of the other group, crosshead guides mounted on the remaining disks of the second group, push-bars mounted in said slides and crossheads for said push-bars mounted in said guides, cam means for operating said push-bars and slides, means to deliver wrappers to said wrapper receiving bars and means to deliver straws to said slides, said slides and said wrapper receiving bars being cooperatively aligned, and means to deliver the packaged straws from the machine.
7. In a straw packaging machine, a rotatable shaft, two groups of disks secured to said shaft, wrapper receiving bars secured to one group of disks, straw receiving slides mounted on some of the disks of the other group, crosshead guides mounted on the remaining disks of the second group, push-bars mounted in said slides and

crossheads for said push-bars mounted in said guides, cam means for operating said push-bars and slides, means to deliver wrappers to said wrapper receiving bars and means to deliver straws to said slides, said slides and said wrapper receiving bars being cooperatively aligned, means to hold the wrappers immovable on said wrapper receiving bars while they are being filled, and means to deliver the filled wrappers from the machine.

8. In a straw packaging machine, a rotatable shaft, two groups of disks secured to said shaft, wrapper receiving bars secured to one group of disks, straw receiving slides mounted on some of the disks of the other group, crosshead guides mounted on the remaining disks of the second group, push-bars mounted in said slides and crossheads for said push-bars and slides, means to deliver wrappers to said wrapper receiving bars and means to deliver straws to said slides, said slides and said wrapper receiving bars being cooperatively aligned, means to hold the wrappers immovable on said wrapper receiving bars while they are being filled, and means to deliver the filled wrappers from the machine, said wrapper holding means comprising suction devices associated with said wrapper receiving bars.

9. In a straw packaging machine, a rotatable shaft, two groups of disks secured to said shaft, wrapper receiving bars secured to one group of disks, straw receiving slides mounted on some of the disks of the other group, crosshead guides mounted on the remaining disks of the second group, push-bars mounted in said slides and crossheads for said push-bars mounted in said guides, cam means for operating said push-bars and slides, means to deliver wrappers to said wrapper receiving bars and means to deliver straws to said slides, said slides and said wrapper receiving bars being cooperatively aligned, means to hold the wrappers immovable on said wrapper receiving bars while they are being filled, and means to deliver the filled wrappers from the machine, said wrapper holding means comprising wrapper-end engaging plates and wrapper retaining peripheral guides and a tension device.

10. In a straw packaging machine, a rotatable shaft, two groups of disks secured to said shaft, wrapper receiving bars secured to one group of disks, straw receiving slides mounted on some of the disks of the other group, crosshead guides mounted on the remaining disks of the second group, push-bars mounted in said slides and crossheads for said push-bars mounted in said guides, cam means for operating said push-bars and slides, means to deliver wrappers to said wrapper receiving bars and means to deliver straws to said slides, said slides and said wrapper receiving bars being cooperatively aligned, and means to hold the wrappers immovable on said wrapper receiving bars while they are being filled, means to deliver the filled wrappers from the machine, said wrapper holding means comprising wrapper-end engaging plates and wrapper retaining peripheral guides and a tension device.

11. In a straw wrapping machine, a roll-of-paper holder, a wrapper printing means, a continuous-wrapper tube forming means, a wrapper tube cutting means for severing the tube into lengths for individual wrappers, wrapper receiving means, straw receiving means, means to deliver straws from said straw receiving means into the wrappers on said wrapper receiving means,

5 wrapper-end sealing means, said printing means including a plurality of alternately acting printing elements, and means to select and deliver the wrapped straws from the machine into a plurality of groups in accordance with the printed matter on the wrappers.

12. In a straw wrapping machine, a roll-of-paper holder, a wrapper printing means, a continuous-wrapper tube forming means, a wrapper tube cutting means for severing the tube into lengths for individual wrappers, wrapper receiving means, straw receiving means, means to deliver straws from said straw receiving means into the wrappers on said wrapper receiving means, 10 wrapper-end sealing means, said printing means including a plurality of alternately acting printing elements, means to select and deliver the wrapped straws from the machine into a plurality of groups in accordance with the printed matter 15 on the wrappers, said selecting and delivering means comprising package gathering fingers, separate delivery chutes, and means cooperative with said fingers and chutes for delivering the gathered packages into their proper delivery chutes.

13. In a straw wrapping machine, a rotatable drum-like unit comprising a shaft, a set of disks secured in spaced relation on said shaft, certain of said disks having transverse grooves symmetrically arranged and spaced apart peripherally, a set of straw receiving members located in said grooves, means to hold said straw receiving members to said grooved disks for endwise movement, crosshead guides connecting others of said disks together, a cam located between said other disks, 35 crossheads slideable in said guides, push-bars connected to said crossheads and movable longitudinally in said straw receiving members, and connections between said crossheads and said cam.

14. In a straw wrapping machine, a rotatable drumlike unit comprising a shaft, a set of disks secured in spaced relation on said shaft, certain of said disks having transverse grooves symmetrically arranged and spaced apart peripherally, a set of straw receiving members located in said grooves, means to hold said straw receiving members to said grooved disks for endwise movement, crosshead guides connecting others of said disks together, a cam located between said other disks, crossheads slideable in said guides, push-bars connected to said crossheads and movable longitudinally in said straw receiving members, connections between said crossheads and said cam, said straw receiving members comprising slides, and cooperative connections between said slides and 55 said cam.

15. In a straw wrapping machine, a rotatable drum-like unit comprising a shaft, a set of disks secured in spaced relation on said shaft, certain of said disks having transverse grooves symmetrically arranged and spaced apart peripherally, a set of straw receiving members located in said grooves, means to hold said straw receiving members to said grooved disks for endwise movement, crosshead guides connecting others of said disks together, a cam located between said other disks, crossheads slideable in said guides, push-bars connected to said crossheads and movable longitudinally in said straw receiving members, and connections between said crossheads and said cam, 60 said straw receiving members having grooves and said push-bars having wings to ride in said grooves to guide the bars in the said straw receiving members.

16. In a straw wrapping machine, a wrapper receiving and holding unit comprising a rotatable

shaft, a pair of disks secured to and spaced apart on said shaft, a set of spaced wrapper receiving bars secured to the periphery of said disks, each of said bars comprising spaced-apart blocks, the blocks having aligning grooves to receive a wrapper therein, the wrapper bridging the spaces between the blocks, means to deliver wrappers to said bars, and means to hold the wrappers in position on the bars while they are being filled.

17. In a straw wrapping machine, a wrapper receiving and holding unit comprising a rotatable shaft, a pair of disks secured to and spaced apart on said shaft, a set of spaced wrapper receiving bars secured to the periphery of said disks, each of said bars comprising spaced-apart blocks, the blocks having aligning grooves to receive a wrapper therein, the wrapper bridging the spaces between the blocks, means to deliver wrappers to said bars, and means to hold the wrappers in position on the bars while they are being filled, 10 said last-named means comprising suction ducts in the bars, a distributing valve device connected with said ducts and with a source of suction for applying suction to the wrappers during a predetermined time while the wrappers are being 20 carried by said bars.

18. In a straw wrapping machine, a wrapper receiving and holding unit comprising a rotatable shaft, a pair of disks secured to and spaced apart on said shaft, a set of spaced wrapper receiving 30 bars secured to the periphery of said disks, each of said bars comprising spaced-apart blocks, the blocks having aligning grooves to receive a wrapper therein, the wrapper bridging the spaces between the blocks, movable wrapper receiving 35 fingers located above said unit, means to place wrappers on said fingers, and means to operate said fingers to lower the wrappers into the grooved bars as they come beneath the wrappers.

19. In a straw wrapping machine, a wrapper receiving and holding unit comprising a rotatable shaft, a pair of disks secured to and spaced apart on said shaft, a set of spaced wrapper receiving bars secured to the periphery of said disks, each of said bars comprising spaced-apart 40 blocks, the blocks having aligning grooves to receive a wrapper therein, the wrapper bridging the spaces between the blocks, movable wrapper receiving fingers located above said unit, means to place wrappers on said fingers, means to operate 45 said fingers to lower the wrappers into the grooved bars as they come beneath the wrappers, and a second set of fingers located above the first set to receive the wrappers between them.

20. In a straw wrapping machine, a wrapper receiving and holding unit comprising a rotatable shaft, a pair of disks secured to and spaced apart on said shaft, a set of spaced wrapper receiving bars secured to the periphery of said disks, each of said bars comprising spaced-apart 60 blocks, the blocks having aligning grooves to receive a wrapper therein, the wrapper bridging the spaces between the blocks, movable wrapper receiving fingers located above said unit, means to place wrappers on said fingers, and means to 65 operate said fingers to lower the wrappers into the grooved bars as they come beneath the wrappers, and fixed wrapper stop members cooperative with the fingers for preventing the wrappers from sticking to the fingers.

21. In a straw wrapping machine, a wrapper receiving and holding unit comprising a rotatable shaft, a pair of disks secured to and spaced apart on said shaft, a set of spaced wrapper receiving bars secured to the periphery of said 70

75

disks, each of said bars comprising spaced-apart blocks, the blocks having aligning grooves to receive a wrapper therein, the wrapper bridging the spaces between the blocks, movable wrapper receiving fingers located above said unit, means to place wrappers on said fingers, means to operate said fingers to lower the wrappers into the grooved bars as they come beneath the wrappers, a second set of fingers located above the first set to receive the wrappers between them, and fixed wrapper stop members cooperative with the fingers for preventing the wrappers from sticking to the upper fingers.

22. In a straw wrapping machine, a wrapper receiving and holding unit comprising a rotatable shaft, a pair of disks secured to and spaced apart on said shaft, a set of spaced wrapper receiving bars secured to the peripheries of said disks, each of said bars comprising spaced-apart blocks, the blocks having aligning grooves to receive a wrapper therein, the wrapper bridging the spaces between the blocks, means to deliver wrappers to said bars, means to hold the wrappers in position on the bars while they are being filled, and means to remove the filled wrappers from said bars, said last-named means including a rotatable shaft and disks on said last-named shaft, said disks having arms to pass through the spaces between the blocks of the bars as the bars approach the removing means, and fixed fingers cooperating with said arms to hold the packages to said last-named disks while being removed from said bars.

23. In a straw wrapping machine, a wrapper receiving and holding unit comprising a rotatable shaft, a pair of disks secured to and spaced apart on said shaft, a set of spaced wrapper receiving bars secured to the peripheries of said disks, each of said bars comprising spaced-apart blocks, the blocks having aligning grooves to receive a wrapper therein, the wrapper bridging the spaces between the blocks, means to hold the wrappers in position on the bars while they are being filled, means to remove the filled wrappers from said bars, said last-named means including a rotatable shaft and disks on said last-named shaft, said disks having arms to pass through the spaces between the blocks of the bars as the bars approach the removing means, and fixed fingers cooperating with said arms to hold the packages to said last-named disks while being removed from said bars, there being two sets of arms on said last-named disks, two package receivers, one having a fixed receiving end cooperative with said removing means and the other including a movable receiving and selecting means operated in timed relation with said removing means to move said movable end into position to receive alternate packages from said receiving means.

24. In a straw wrapping machine, means for forming continuously a wrapper tube from a continuous strip of paper, means for severing the tube into wrapper lengths, means for filling the wrapper lengths with straws, and means for sealing the ends of the wrappers; in combination with a mechanism to print the strip of paper in

alternately different sections before the tube is formed.

25. In a straw wrapping machine, means for forming continuously a wrapper tube from a continuous strip of paper, means for severing the tube into wrapper lengths, means for filling the wrapper lengths with straws, means for sealing the ends of the wrappers; in combination with a mechanism to print the strip of paper in alternately different sections before the tube is formed, and means for filling the severed sections of tubes with straws, and means to deliver into separate receptacles the wrapped straws according to the printed matter thereon.

26. In a straw wrapping machine, a rotatable shaft, a wrapper receiving member carried by said shaft and having superficial grooves in which the wrappers are placed, a straw receiver carried by said shaft and having superficial grooves in endwise alignment with the grooves of the first mentioned grooved member, straw receiving slide bars mounted in the grooves of the straw receiving member to be endwise slidable toward and from the wrapper receiving member, push bars operating in and through said slide bars to force the straws from said slide bars into the wrappers, means for moving said slide bars into endwise engagement with the wrappers prior to the introduction of the straws into the wrappers, means for delivering straws to said slide bars, means for delivering wrappers to the wrapping receiving member, means sealing the ends of the filled wrappers, and means for removing the filled wrappers from the machine.

27. In a straw wrapping machine, the combination with the drum-like structure on which the straw wrappers are filled and sealed, of means for removing the filled wrappers from the drum-like structure, said means comprising package gathering fingers, separate delivery chutes, and means for cooperating with said fingers and chutes for delivering the gathered packages alternately into their respective delivery chutes.

28. In a straw wrapping machine wherein a continuous roll of paper is printed differently in successive areas, formed into a continuous tube which is then severed into successive sections, filled with straws and sealed up; mechanism for separating the wrapped articles into groups corresponding to the differently printed areas and delivering the same from the machine in their separated groups.

29. In a straw wrapping machine wherein is provided a roll-of-paper-holder, a plural printer, a wrapper tube forming and severing mechanism, and means to fill the successive severed tube sections with straws and seal said sections; the combination therewith of a selective delivery mechanism for separating and delivering the filled packages into groups corresponding in number to the plurality of the printer, in virtue of which all like-printed wrappers only will be delivered together.
